UNITED STATES PATENT OFFICE

2,463,433

REGISTERING COIN BANK

Fred Schnabolk, Brooklyn, N. Y., assignor to
 Kalon Radio Corp., Brooklyn, N. Y., a corpora-
 tion of New York

Application August 22, 1946, Serial No. 692,292

2 Claims. (Cl. 235—100)

1

This invention relates to registering toy banks. One object of the invention is to provide a toy bank of the character described having improved means of a particularly simple and efficient nature whereby the toy bank is adapted to be highly compact and inexpensive in manufacture.

Another object of the invention is to furnish a toy bank having very few movable parts and capable of long operation without getting out of order, and serving nevertheless to control the insertion and removal of the coins and to register the amount contained in the bank.

Another object of the invention is to provide a toy bank, the parts whereof are so constructed and arranged as to greatly facilitate the assembling thereof.

Another object of the invention is to furnish a toy bank the casing of which may be made of very light gage metal suitably reinforced by the registering gear of the bank to reliably resist any tendency against improperly forcing open the door of the bank.

Another object of the invention is to provide a toy bank having its coin removal door and the locking means therefor arranged and coordinated in an improved manner for increased reliability, and to permit opening of the door only when the bank has received a predetermined number of coins.

A particular object of the invention is the provision of an improved toy bank such that the insertion of a coin thereinto for actuating the door locking mechanism is impossible unless the door is first closed, thus precluding a condition where the prematurely closed lock may prevent closing of the door and consequently cause possible breakage of the bank.

Another object of the invention is to furnish a toy bank having improved spring means, preferably of one-piece construction, actuatable at least in part by a coin and providing gear turning and locking pawls preferably so engaged with a registering or door-locking gear as to be maintained always in operative relation to the teeth of the gear.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated

2

by the same reference characters throughout the several views.

In the drawings:

Figure 1 is a view in front elevation showing a toy bank embodying the invention.

Fig. 2 is a view in rear elevation thereof.

Fig. 3 is a top plan view of the toy bank of Fig. 2.

Fig. 4 is an inside view in elevation of the front casing section with its operating parts in position 10 for opening the rear door.

Fig. 5 is an inside view in elevation of the rear casing section showing the coin removal door.

Fig. 6 is a perspective view of the coin operated spring means for controlling the registering or 15 door-locking gear.

Fig. 7 is a fragmentary view like that of Fig. 4 with parts in section and showing a coin partly inserted to actuate the spring means, with the gear advanced to a door-locking position.

Fig. 8 shows the opposite face of the gear carrying certain registering indicia along the circular legend areas.

Fig. 9 is an enlarged sectional view taken on the line 9—9 of Fig. 1.

Fig. 10 is a fragmentary sectional view taken through the center of the coin bank and showing the coin removal door in open position.

Fig. 11 is an enlarged fragmentary sectional view showing a pawl with an aligning means laterally engaging its gear.

Fig. 12 is a fragmentary view partly in section and partly in elevation with a coin illustrated in dot-dash lines to show the seating and guiding cooperation of the spring means with the coin in 35 course of actuation of the former by the coin.

The advantages of the invention as here outlined are best realized when all of its features and instrumentalities are combined, but useful embodiments may be produced involving less than 40 the whole.

It will be obvious to those skilled in the art to which the invention appertains, that the same may be incorporated in several different constructions. The accompanying drawing, therefore, is submitted merely as showing a preferred 45 exemplification of the invention.

Referring in detail to the drawing, 15 denotes a toy bank embodying the invention. The same includes a casing 16 comprising a box-like section 17 having a front wall 18 and a side wall 19 a portion of which constitutes a top wall 20 having a coin receiving slot 21. For compactness, the corner portions of the casing section are angular as shown at 22. A companion casing section or 50 rear cover 23 is of generally similar configuration

and includes a wall 24 with certain marginal flanges 25 which are separate of each other and are adapted to be sprung inwardly to be snugly received in the section 17. The width of these flanges may be substantially less than the depth of the front section 17 and they may have teats 26 outwardly struck therein for snap-in engagement in holes 27 of the side walls 19. Intermediate of the flanges 25, the angular portions 28 extend outwardly sufficiently to abut the rear edges of the angular portions 22 of the front section to afford stops to limit the entrance of the cover 23 with the teats 26 engaged in their holes 27. Within the front casing section 17 is a gear 30 which may be made of relatively heavier gage metal than the casing. This gear is formed with any suitable or relatively square teeth 31, the adjacent peripheral portion of the gear being inwardly bent at 32 in order to slightly dish the gear and space the teeth 31 away from the front wall 18 with which the gear is otherwise in direct sliding contact. A rivet or eyelet 33 interconnects the gear with the front wall 18 so that the latter is in generally central relation to the front casing section 17. It will be understood that the gear is of sufficient size and has a sufficient number of teeth to correspond to the predetermined number of coins that are to be deposited in the toy bank. The face of the gear which confronts the wall 18 is provided with indicia to indicate the amount of money deposited, and where a coin is inserted each day, the indicia may also indicate the days of the week in recurrent series. In Fig 8 the circular area defined by dotted lines and bearing the legend "amount" at 34, contains a circular series of numerals each corresponding to a tooth 31. A similar area at 35 bearing the legend "day" indicates the days of the week, as Sunday, Monday, etc., corresponding to the different teeth 31. If the bank is to remain locked until fifty dimes have been deposited, then the gear will have fifty teeth, and there will be fifty numerals at 34 of the amounts deposited, and at 35 there will be 50 markings for the different days of the week. In the front wall 18 are formed the window openings 36, 37 corresponding respectively to the indicia 34, 35 for a step by step display of indicia corresponding to the position of the gear and the number of coins received. To avoid marring of the indicia, the contacting faces of the gear and of the front wall may be highly smooth or suitably treated for that purpose. When the fifty coins have been deposited, a slot opening 38 in the gear 30 may lie in the vertical plane of its axis and in register with a similar slot opening 39 in the front wall 18 as shown in Figs. 1 and 4, in order to release a coin door to permit the same to be opened for removal of the coins as herein-after described. When the slot openings 38 and 39 are out of register with each other, as shown in Fig. 7, the coin removal door is locked.

Coordinated in an improved manner with the coin slot 21 and the gear 30 is a spring means 40 which is preferably a one-piece construction. The same may consist of a strip member 41 having a hole 42 whereby it is secured to the top wall 20 as by a rivet or eyelet 43. In Fig. 4 this point of securement is remote from the coin slot 21, the spring means extending at least partially thereunder. At its other end, the spring means is formed with an extension 44 to obtain additional bearing against the front wall 18 with which it lies in contact, and thus a single rivet may suffice to securely hold the spring against lateral shifting. Beginning at a point adjacent

to the rivet, the strip member 41 is slotted at 45 to form a relatively narrow tongue 46 extending rightward in relative proximity to the top wall 20, except that it is bent at 47 to form a downwardly inclined pawl 48 for engaging the teeth of the gear 30 in a sufficiently strong manner to resist a strong force tending to turn the gear 30 in either direction. The right angle extension 49 at a side edge of the pawl 48 nearest to the front wall 18 projects to lie between the latter and the teeth 31 of the gear. While the gear may thus be caused to spring slightly away from the wall 18, the space for the finger 49 is provided mainly by the inwardly dished shape of the gear at 32 as further shown in Figs. 9 and 11. Along a prolongation of an edge of the slot 45, the strip member 41 is reduced in width to form the substantially narrower strip sprung section 50, the latter having a downwardly offset portion 51 to add to the resilience of the section 50. By reason of the reduced width of the section 50, the same clears the coin slot 21 which is formed adjacent to the front wall 18, but in sufficiently spaced relation thereto, in order to clear the gear 30. At its free end portion, the section 50 is increased in width at 52, this portion being downwardly inclined so that its extreme end portion 53 constitutes a pawl for the gear 30. At right angles to the portion 53 there is provided a finger 54 connected thereto and adapted to lie between the gear and the front wall 18 in the same manner and for the same purpose as described for the finger 49, and as illustrated in Fig. 11. These fingers 49 and 54 cooperate to maintain the strip member 41 against lateral movement and to maintain the same proper in operative relation to the gear and to the coin slot. Further, the pawls 48 and 53 cooperate with each other to simultaneously engage the gear teeth in a sufficiently strong manner to resist any ordinary force tending to turn the gear. However, when a coin is inserted, the pawl 53 serves to advance the gear one tooth in a clockwise direction with the pawl 48 yielding upwardly as hereinafter described.

The operation of the spring means 40 by a coin and the structure involved will be best understood by comparing Figs. 4 and 6 with Figs. 7 and 12, the latter including a coin 60 inwardly projected to a point immediately before release into the coin bank, with the gear 30 almost advanced to the full extent of a tooth. For this purpose the spring means is provided with coin seating and guiding means in advance of the pawl 53 but adjacent to the pawl arm 52. Such seating and guiding means 61 includes a downwardly inclined guide portion 61, the arrangement of which is facilitated by upwardly bending the spring means at 62 at the junction between the spring section 50 and the pawl arm 52. The guide portion 61 is preferably of a channel shape shown in Figs. 6 and 12 and which increases in depth toward its free end. This channel portion underlies that end of the coin slot 21 which is nearest to the actuator pawl 53, as may also be seen in Fig. 3 and its purpose is to avoid lateral deflection of the coin especially into the path of the gear teeth 31 which are close nearby. As the coin moves downwardly to deflect the spring as in Fig. 7, the strain on the relatively thin metal becomes considerable and the coin seats evenly instead of merely on an edge of the metal, thereby reducing wear and distortion. Cooperating with the channel portion 61 is a lug 63 connected to spring section 50 and located adjacent to the opposite end of the coin slot, this lug being spaced from the gear 30 and

serving to downwardly guide the coin against shifting about in the channel portion. To obtain an accurate advance of the gear 30, the coin 60 operates in the manner of a wedge or cam between the channel portion 61 and an end 64 of the coin slot 21, as shown in Fig. 7, the coin being free of or spaced from the right hand end of the coin slot. With the usual knurled coin, the same pivots about the edge at 64 and rolls in the channel guide 61. The relationship produced is such that the coin tends to elongate the bend or offset portion 51 of the spring means at the same time that the wedging action keeps it securely seated in the channel portion 61 for exerting downward pressure on the arm 52 to advance the pawl 53. As the coin passes dead centre, the gear 30 has been advanced a tooth and the pawl 48 snaps down to lock the gear against reverse movement; then the coin drops into the bank chamber, releasing the spring means 40 so that the pawl 53 is retracted by return of the spring to snap into engagement with its next upper tooth, both pawls being thus again in the initial position shown in Fig. 4. More specifically, when the spring is depressed by the coin, the pawl 53 advances the gear one tooth causing a tooth to pass the pawl 48, the superior force of the pawl 53 overcoming the substantial stiffness of the pawl 48, and the latter then snapping into locking engagement with the next succeeding tooth to again lock the gear. This action is feasible because both pawls operatively extend in the same angular direction and because of the angular relation of the different pawls to the respective teeth engaged thereby which permits advance of the pawl 53 to overcome the pawl 48. Retraction of the spring to its normal positions causes retraction of the pawl 53 with the latter easily riding over a tooth to engage the next succeeding tooth without disturbing the gear which remains locked by the superior force of the relatively stiff pawl 48. In this normal position, both pawls are in engagement with the gear. The tolerances for the coin are rather small, and if the coin were able to shift about, the device would not operate satisfactorily. Hence the importance of the guide means 61, 63 and also of the gear engaging fingers 49, 54 which with the gear and wall 20 serve as a movable guide means for the spring device to maintain it in accurate relation to the coin slot without interfering with the operation of the spring and gear.

The coin removal door is mounted on the rear or cover section 23 of the casing and is shown in closed position in Figs. 5 and 9 and in open position in Fig. 10, a portion of its locking means including the slots 38, 39 in open position in Figs. 1 and 10 and in closed position in Fig. 7. The rear wall 24 may have a rectangular opening 66 having an outwardly offset marginal clearance portion 67 at its lower edge and having inward extending flanges 68 along its side edges serving to stiffen the same and being so narrow as not to impede removal of the coins but being increased in width at their upper ends to provide bearing sections 69 having upwardly opening slots or bearing holes 70. The door 65 is reinforcingly flanged at 71 along its side edges, these inward extending flanges being narrow but increased in width at their upper portions 72 from which are outwardly struck teats or eyes 73 adapted to freely enter the openings 70 for mounting the door for angular movement with the door flanges 71 sliding between the casing flanges 68 to produce a reinforced mounting. At its lower edge the door is inwardly offset at 74 to seat in the offset 67 of

the rear wall 24 with the door lying in the plane of the latter. To this offset portion is secured a bar 75 carrying a rigid pin 76 registering with the opening 39 in the casing front wall 18 as the door 65 swings inwardly to open position. For closing the door, a strip spring 77 is riveted to the rear wall 24 at 78, this spring being preferably bent or bowed as at 79 so that it may serve as a stop against the gear 30 to limit inward opening movement of the door without strain or distortion on the pin 76. The free end of the bowed portion is adapted to bear strongly against the door at the angle 80 of the offset 74 or against the bar 75 thus realizing the function of urging the door 65 downwardly to retain the trunnions 73 in the open bearing holes 70.

The operation of the coin bank will now be briefly described. The operator inserts a coin through the coin slot 21 and presses hard on it to cause deflection of the spring means 40 and consequent rotation of the gear 30 for one tooth. The indicia means 34, 35 indicates the operation at the corresponding windows 36, 37, and since these indicia are directly on the gear 30, a simple and accurate structure is afforded for this purpose. When a sufficient number of coins have been deposited to represent a predetermined amount of money, the gear 30 has made a complete rotation, whereupon the slots 38, 39 in the gear 30 and in the front casing wall respectively are in register and in proper aligned relation with the pin 76 of the rear coin removal door 65. The latter is maintained closed by the spring 77 to prevent spilling of the coins, and therefore the operator pushes the door inward as shown in Fig. 10, the pin 76 entering the slots which are provided for clearance, and the operator may now shake the coins out of the bank. Upon release, the door is instantly closed by the spring 77 so that the coin bank is again ready for further deposits. However, should the operator continue pressing the door inward inadvertently or otherwise, it will not be possible for him to insert a coin because the pin 76 will prevent rotation of the gear 30 and accordingly the spring means 40 will not be able to deflect downwardly to pass the coin. It is therefore impossible to close the locking means to a position which would prevent closing of the door as has occurred in devices heretofore known. Upon passage of the first coin, the gear 30 has been moved sufficiently so that the slot 38 therein is no longer in alignment with the pin 76. The door is thus locked closed because the pin will abut the gear.

Accordingly the gear may be made of relatively heavier gage metal than the bank casing so that the latter may be light in weight and it nevertheless affords a support or reinforcement for the gear at the point of abutment with the pin 76. The free end of the latter has sliding contact with the adjacent face of the gear as the gear turns, and this contact may be sufficiently accurate so that the door does not move even to a small degree. By pivoting the door 65 near the top of the casing, the pin 76 is remote from the coin entrance and the door may be made sufficiently long to afford an ample opening and leverage for the opening and closing of the door. By reason of the split or open bearings of the stud portion 73 in the slot 70, a quick assembly is possible, with the spring 77 acting longitudinally on the door at 80 to maintain the bearing portions in engagement, the spring being bowed at 79 to freely lock with the door at 80 and to form a stop against the gear limiting inward movement of the

door and avoiding any tendency to bending of the pin 76 against an edge of the slot openings 38, 39. The flanges 63 and 71 are used not only as reinforcements, but constitute a track or guide for the door. A unitary spring means 40 provides the cooperating advancing and locking pawls 53 and 45 respectively, and when the spring means is downwardly deflected by a coin as in Fig. 7, downward tension on the pawl 48 is increased, and both of these pawls may also cooperate to lock the gear against rotation in either direction except by operation of a coin. The latter acts in a wedgelike manner between an end 64 of the coin slot 21 and a downwardly sloping channel seat 81 of the spring means, the latter cooperating with the lug or wing 63 on the coin slot to accurately guide the coin against lateral shifting or tilting, whereby an accurate relation is always maintained between the points at 61 and 64. The gear 30 is utilized as an anchorage for the relatively long spring means by reason of the portions 49 and 54 engaging between the front wall 18 of the casing and the dished peripheral portion of the gear, thereby assuring precision of the coin with relation to the points 61 and 64, and also assuring that the pawls are always in accurate relation to the gear teeth. The device can be assembled in two halves as shown in Figs. 4 and 5 after which it is merely necessary to connect these two halves together in any suitable manner as by teats 26 carried by the resilient flanges 25 so as to be adapted to be snapped into the perforations 27 in the side walls of the main casing section 17.

I claim:

1. A coin bank having a casing having a coin slot, a coin registering means therein including a rotary gear, and a one-piece strip spring fastened at one end to the casing at a point remote from the slot, the spring being otherwise relatively free, the spring extending from said point toward and substantially beyond the slot in the general direction of the length of the latter, the spring comprising a resilient tongue pawl portion for locking said gear, the locking pawl portion being so closely adjacent to the fastening point as to be quite stiff, said locking pawl portion being adjacent to the near end of the coin slot, the spring having a pawl portion for advancing gear, the advancing pawl portion being substantially beyond the remote end of the coin slot, the spring having a section intermediate of the pawl portions, said section having a temporary seating portion for a coin entering the slot, the seating portion being adjacent to the advancing pawl portion and the remote end of the coin slot, the seating portion cooperating with the near end of the slot to temporarily seat the coin by a wedging action of the latter therebetween, and the forcing in of the coin causing elongation of the spring, the spring having a bent portion adjacent to the fastening point and being free of the locking pawl portion, said bent portion tending to deflect under

tension to permit the said elongation, the forcing in of the coin, also causing a deflection of the spring in a direction away from the coin slot to cause advance of the advancing pawl portion, 5 said intermediate section having a normal position with both of the pawl portions being in engagement with the gear, said section being deflected from said normal position by pressure of the coin on the seating portion to actuate the advancing pawl portion to move the gear one tooth with the locking pawl portion being thus caused to snap into engagement with a succeeding adjacent tooth to again lock the gear while the coin passes and releases the seating portion 10 for a return of the intermediate section to its normal position accompanied by a retraction of the advancing pawl portion to snap over and engage the next adjacent tooth of the gear which remains locked by the locking pawl portion.

20 2. A coin bank having a casing having a coin slot, a coin registering rotary gear, and a one piece strip spring fastened at one end to the casing at a point remote from the coin slot, the spring being otherwise relatively free, the spring 25 extending from said point toward and beyond the coin slot lengthwise of the latter, the spring comprising a resilient locking pawl for the gear so close to the fastening point as to be quite stiff, the spring having an advancing pawl for the gear spaced substantially beyond the far end of the coin slot, both pawls pointing in the same angular direction, the spring having a section intermediate of the pawls, the section having a temporary coin seating portion adjacent to the far end of 30 the slot, the section having a normal position with both pawls engaged with the gear, the seating portion under pressure by an entering coin causing deflection of the intermediate section until the coin snaps past the seating portion to 35 enter the casing and thus to release the section, the intermediate section upon occurrence of said deflection causing the advancing pawl to move to turn the gear one tooth with sufficient force to cause the locking pawl to snap into locking engagement with the next succeeding tooth, retraction of the section to normal position causing retraction of the advancing pawl to engage the next succeeding tooth, while the gear remains 40 locked by the locking pawl.

45 50 FRED SCHNABOLK.
